Primary Examiner — Calvin E Vansant*Assistant Examiner* — Mark T. Philipp(74) *Attorney, Agent, or Firm* — Crowell & Moring LLP(57) **CLAIM**

The ornamental design for a compressor as shown and described.

DESCRIPTION

FIG. 1 is a reduced front, top and right side perspective view of a compressor according to the design;

FIG. 2 is a front elevational view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a rear elevational view thereof; and,

FIG. 8 is an enlarged cross-sectional view taken along line 8-8 of FIG. 2.

The broken lines illustrate portions of the compressor that form no part of the claimed design.
